UNITED STATES PATENT OFFICE.

LOUIS FRANK HERING, OF POMONA, CALIFORNIA, ASSIGNOR OF ONE-HALF TO ALFRED KONJETZKY, OF POMONA, CALIFORNIA.

PROJECTILE.

1,110,933.

Specification of Letters Patent.

Patented Sept. 15, 1914.

Application filed June 30, 1914. Serial No. 848,263.

To all whom it may concern:

Be it known that I, LOUIS F. HERING, a citizen of the United States, and a resident of Pomona, in the county of Los Angeles and State of California, have made certain new and useful Improvements in Projectiles, of which the following is a specification.

My invention is an improvement in projectiles, and has for its object to provide a device of the character specified, designed to be discharged through the air, by means of a plurality of guns of large caliber and great power, and wherein the projectile is in the form of a wheel laden with explosives, timed to discharge at a predetermined moment, and provided with laterally extending swords or sabers, and wherein mechanism is provided for supporting the projectile, and for imparting rotation to the fly wheel before it is discharged from the guns, and wherein other mechanism is provided in connection with the guns for supporting and guiding the projectile at the commencement of its flight.

25 In the drawings: Figure 1 is a top plan view of the improved projectile, and the discharging means, Fig. 2 is an end view with parts in section, Figs. 3 and 4 are sections on the lines 3-3, and 4-4, respectively of Fig. 1, Fig. 5 is a section on the line 5-5 of Fig. 4, and Fig. 6 is a side view of the wheel with parts in section.

The present embodiment of the invention is shown in connection with a pair of guns 35 1 and 1^a, of suitable size and caliber, and supported by a common carriage 2. The bores of the two guns are exactly parallel, and each gun is provided with a counter-bored portion 3 at its breech, for receiving a blank cartridge 4. The breech of each of the guns is closed by a door 5 and 5^a respectively, the doors being hinged to the guns, as indicated at 6, and the doors are opened by means of a common bar 7, pivoted to lugs 8 on the doors, and having a hand hold 9 for convenience in operating the same. Each gun is partially closed at its muzzle; that is the bore is reduced at the muzzle, as indicated at 10, and each gun has a vent or exhaust port 11 intermediate its ends and in its upper side. A piston or plunger 12 is mounted in each gun, each piston or plunger fitting the bore of the gun, and each

piston or plunger is secured to one end of a piston rod 13. A coil spring 14 encircles each piston rod 13 between the plunger or piston 12 and the shoulder 15 formed between the reduced portion 10 and the body of the bore, each spring acting normally to press the piston or plunger toward the cartridge. Each gun is also provided with a telescope sight 16, and the outer end of each of the piston rods has rigidly connected therewith a yoke, each yoke comprising a body 17 rigid with the rod, and arms 18 and 18^a extending approximately parallel with each other. The lower arm 18^a of each of the yokes is provided with laterally spaced parallel depending ribs 19, and grooved wheels 20 are supported by the ribs, each wheel being journaled on a journal pin 21 held in bearings 22 in the ribs. The grooved wheels 20 are arranged to run on the heads of rails 23, and the rails 23 are parallel with each other and in vertical alinement with the piston rods 13 of the guns. Each rail 23 is connected at its inner end to a bracket 25 connecting the muzzles of the guns, and extending below the said muzzles.

A channel plate 26 extends from the bracket 25 longitudinally of the guns and between and below the same, and the arms 24 which support the rails are integral with the channel plate 26. Referring to Fig. 2 it will be seen that the arms 24 are of double angle material, each arm comprising two portions parallel but offset laterally with respect to each other and connected by an integral connection. At one side the channel plate and the bracket have an integral extension 27, for supporting a motor 28, the motor being an electric motor in the present instance, and interposed in an electrical circuit, consisting of lead wires 29 and 29^a. A switch 30 is interposed in the circuit for closing the same, and the current is supplied by a battery 31, or any other desired source of energy.

The projectile proper comprises a wheel consisting of side plates 31 and 31^a arranged in spaced relation and rigidly connected together. A sleeve or hub 32 is rigid with the side plates and extends laterally beyond the outer faces of the same, and a shaft 33 is journaled in the sleeve. The shaft is separated from the sleeve by means of ball bear-

ings 34, and the sleeve is provided at one end with an annular marginal rib 35, the said rib being a friction disk and frictionally engaging a similar disk 36 on the motor shaft 37 of the motor. Sleeves 38 are arranged on each side of the wheel, and concentric with the shaft and the sleeve or hub 32, and each sleeve is separated from the hub 32 by other ball bearings 39. The ball bearings 39 are in radial alignment with the bearings 34, and the shaft 22 has annular ribs 40 at its ends, the said ribs abutting the ends of the sleeve 32 to prevent longitudinal movement of the sleeve with respect to the shaft. The sleeve 32 extends through the side plates, and the side plates are connected near their peripheries by a rim 41. Blades 42 are arranged spirally on the wheel between the side plates and outside of the rim 41, and the interior 20 of the wheel, that is that space within the rim 41 and between the side plates is designed to be filled with explosives 43, connected, as indicated at 44, and designed to be ignited or exploded at a predetermined 25 time. The explosive agents or projectiles 43 may be embedded in the explosive agent, indicated at 45. Sabers or sword blades 46 are connected with the ends of the shafts 33, and the said blades extend longitudinally 30 from the ends of the shaft, each blade having its front edge beveled, as indicated at 47.

In operation, the guns 1 and 1^a are loaded with blank cartridges, and the projectile is placed as shown in Figs. 1, 2 and 4. The arms 18 and 18^a of the yokes engage the sleeves 38, and the projectile rests between the yokes, the said yokes being supported by the grooved wheels 20 on the rails 23. It will be understood that the projectiles and the explosive agents are arranged in the wheel before it is placed. After the doors 5 have been closed, and the projectile ready for flight, the switch 30 is closed, and the motor shaft 37 will begin to rotate. As soon 45 as the shaft 33 has attained the desired rate of speed, the guns are fired. The pistons or plungers 12 are driven forward by the expansion of the gases in the bore of the gun, and the yokes, 17-18-18^a are driven 50 quickly forward, the wheels 20 running on the rails 23. The wheel and connected parts are thus discharged into the air, and it will be obvious that the explosive agent in the wheel may be timed to explode at any predetermined point. When this happens the entire projectile will be driven in all directions, thus causing great damage in the ranks of the enemy. The saber blades will also cause much damage as the projectile 55 travels forward. As soon as the pistons 12 pass the exhaust ports or vents 11, the expanded gases will escape, and the springs 14 will drive the plunger rearwardly, withdrawing the yokes and placing the device in 60 readiness for another projectile.

I claim:

1. A device of the character specified, comprising a wheel, a shaft upon which the wheel is journaled, said shaft having at each end a longitudinally extending blade, a hub at the center of the wheel and extending on both faces thereof and journaled on the shaft, sleeves journaled on the ends of the hub at opposite sides of the wheel, means for launching the wheel and connected parts through the air, said means comprising guns arranged with their bores parallel, a plunger in each gun, each plunger having a plunger rod extending through the muzzle of the gun and beyond the said muzzle, and having a yoke at its outer end, a spring for returning each plunger, each gun having an exhaust opening intermediate its ends, a bracket connecting the muzzles of the guns and having a track rail in vertical alignment with the axis of each gun, each yoke having grooved wheels running on the adjacent track rail, and means for imparting rotation to the wheel before it is discharged, said means comprising a motor, a disk connected with the motor, and a disk rigid with the sleeve and engaging the disk of the motor.

2. A device of the character specified, comprising a wheel, a shaft upon which the wheel is journaled, said shaft having at each end a longitudinally extending blade, a hub at the center of the wheel and extending on both faces thereof and journaled on the shaft, sleeves journaled on the ends of the hub at opposite sides of the wheel, means for launching the wheel and connected parts through the air, said means comprising guns arranged with their bores parallel, a plunger in each gun, each plunger having a plunger rod extending through the muzzle of the gun, and beyond the said muzzle, and having a yoke at its outer end, a spring for returning each plunger, each gun having an exhaust opening intermediate its ends, a bracket connecting the muzzles of the guns and having a track rail in vertical alignment with the axis of each gun, each yoke having grooved wheels running on the adjacent track rail.

3. A device of the character specified, comprising a wheel, a shaft upon which the wheel is journaled, said shaft having at each end a longitudinally extending blade, a hub at the center of the wheel and extending on both faces thereof and journaled on the shaft, sleeves journaled on the ends of the hub at opposite sides of the wheel, means for launching the wheel and connected parts through the air, and means for imparting rotation to the wheel before it is discharged, said means comprising a motor, a disk connected with the motor, and a disk rigid with the sleeve and engaging the disk of the motor.

4. A device of the character specified, comprising a wheel, a shaft upon which the wheel is journaled, said shaft having at each end a longitudinally extending blade, a hub at the center of the wheel and extending on both faces thereof and journaled on the shaft, sleeves journaled on the ends of the hub at opposite sides of the wheel, and means for launching the wheel and connected parts through the air. 40
5. In a device of the character specified, a launching device comprising a pair of cylinders having exhaust openings intermediate their ends arranged with their bores in parallelism, a plunger in each cylinder and adapted to be moved longitudinally thereof by expanding gases, a spring for returning each plunger, a rod connected with each plunger and extending beyond the cylinder and having a yoke at its outer end, a spring for returning each plunger, a track rail in vertical alinement with the axis of each cylinder, each yoke having wheels running on the adjacent track rail, and said yokes being adapted to engage the article to be launched. 50
6. In a device of the character specified, a launching device comprising a pair of cylinders having parallel axes and having exhaust openings intermediate their ends, a plunger mounted for longitudinal movement in each cylinder, and adapted to be driven in one direction by expanding gases, a spring for returning each plunger, a yoke outside each cylinder at the end remote from the plunger and rigidly connected with the plunger, a track rail below each yoke, each yoke having wheels for engaging the ad- 55
5. In a device of the character specified, a projectile comprising a shaft provided at each end with a longitudinally extending sword or blade, a wheel having a hub journaled on the shaft and having a central annular chamber adapted to contain explosives and projectiles, and having spiral blades on its periphery, the hub having means at one end for engagement by a motor to rotate the wheel, and bearing sleeves journaled on the ends of the hub for engagement by launching apparatus. 60
8. In a device of the character specified, a projectile comprising a shaft provided at each end with a longitudinally extending sword or blade, a wheel having a hub journaled on the shaft and having spiral blades on its periphery, the hub having means at one end for engagement by a motor to rotate the wheel, and bearing sleeves journaled on the ends of the hub for engagement by launching apparatus. 65
9. In a device of the character specified, a projectile comprising a shaft provided at each end with a longitudinally extending sword or blade, a wheel having a hub journaled on the shaft, the hub having means at one end for engagement by a motor to rotate the wheel, and bearing sleeves journaled on the ends of the hub for engagement by launching apparatus. 70
